UNITED STATES PATENT OFFICE

BRUNO MAX ALFRED TREBES, OF BERWYN, ILLINOIS, ASSIGNOR TO WESTERN ELECTRIC COMPANY, INCORPORATED, OF NEW YORK, N. Y., A CORPORATION OF NEW YORK

APPARATUS FOR COVERING CORES

Application filed October 11, 1927. Serial No. 225,458.

This invention relates to an apparatus for covering cores, and more particularly to an apparatus for applying an insulating covering to an electrical conductor.

5 Objects of the invention are to provide an apparatus by which fibers may be applied directly to a core without preliminarily fabricating the fibers into another form such as spinning them into a yarn.

10 The invention contemplates the provision of an apparatus in which a roving of cotton is separated into its individual fibers which are carried to the strand or core by a column of air where they are revolved until their ends 15 are caught by the fibers already on the core whereupon they are wrapped about the core with a combing action. After the fibers are applied they are polished on the core to give them a neat and finished appearance.

20 It is believed that a complete understanding of the invention may be had by reference to the following description taken in conjunction with the accompanying drawing, in which

25 Fig. 1 is a longitudinal sectional view of the apparatus;

Fig. 2 is a cross sectional view taken on line 2—2 of Fig. 1;

Fig. 3 is a cross sectional view taken on line 30 3—3 of Fig. 1;

Fig. 4 is a modified form of the parts shown in Fig. 3, and

Fig. 5 is a longitudinal section through the parts shown in Fig. 4.

35 Referring to the drawings in which the same reference characters designate similar parts in the several views, a stationary head 11 of the fiber applying apparatus is shown supported by an arm 12 on a frame of any suitable character (not shown). The material in

40 the form of a sliver or roving is fed into the apparatus by a pair of corrugated rollers 13—13 driven by any suitable source of power at a speed which determines the amount of material fed into the apparatus and therefore

45 the thickness of the fibrous covering on the strand. The material passes from the feed rolls 13 into a separating chamber 14 in which a separating wheel 15 having a plurality of paddle arms is rotatably mounted. A pair of

oppositely spaced arms 16 are provided with a plurality of pins upon their ends which upon the rapid rotation of the wheel 15 serve to separate some of the fibers upon each rotation which are then further separated and scattered by the remaining arms of the wheel. From the separating chamber 14 the fibers are carried by a current of air created by a fan 17 into a funnel 18 from where the fibers are delivered into a rotating housing of the machine indicated generally at 21.

55 The rotating housing of the machine which may be driven by a gear 19 from any suitable source of power is mounted in a bearing 22 supported by the frame (not shown) of the machine. The rotatable housing 21 is provided with a rectangular aperture 24 in which an applicator and polishing unit, consisting of a removable section 25 which carries an applicator 26 and a polisher 27, is mounted. 60 When the removable section 25 is in place in the machine a ring 29 is forced by a spring 30 over a portion of the aperture to hold the section 25 firmly in place.

65 The applicator 26 is mounted in a cylindrical opening of the section 25 and comprises a plurality of cylindrical combs 33 mounted on a cross-shaped support 23 having a central opening arranged in graduated sizes from the outer comb having the largest diameter and greatest height to the inner comb having the smallest diameter and least height. The combs may be made of woven wire of a fine mesh in which the longitudinal wires project above the uppermost horizontal wire forming a plurality of pin-like projections which constitute in effect a circular comb. Immediately underneath the applicator, the polisher 27 is located which comprises a pair of blocks 34 having grooves on their adjoining surfaces which form a circular aperture through which the covered core 60 is drawn.

70 The blocks 34 are held in place by pairs of parallel hinges 35 which maintain the surfaces of the blocks parallel at all times. The hinges on the opposite sides of a block are connected by a web 36 so that the upper surface of the polisher presents a substantially continuous flat surface. The polisher blocks

34 are urged upwardly against the covered core by means of a pair of springs 38.

Underneath the removable section 25 a stuffing box 41 is provided having a hollow channel 42 on its interior surface which connects with the interior of the rotatable portion of the machine through apertures 43, allowing the fan 17 which is connected to the hollow ring to maintain a current of air through the entire apparatus.

10 A modified form of polisher is shown in Figs. 4 and 5 in which the polisher blocks 44 are mounted in a polisher cylinder 45 having a conical opening therein. The blocks are urged upwardly by a spring 46 tending to hold them in firm engagement with the conductor.

15 The operation of the apparatus is as follows: The conductor 60 may be given a thin coating of molten rubber or the like to render it slightly sticky in starting the applying operation. This is done only when a new conductor is placed in the machine and need not be repeated every time the machine is stopped.

20 25 A roving or sliver of cotton, silk or asbestos fibers is then fed between the rolls 13 and is delivered in the separating chamber 14 where the sliver is completely separated into its individual fibers. From the separating chamber

30 35 40 45 50 55 60 65 70 75 80 85 90 95 100 105 110 115 120 125 130

the fibers are carried into the funnel 18 by the current of air maintained through the apparatus by means of the fan 17 depositing them in the applicator 26 which is rotated at a high velocity. When the fibers come in contact with the rapidly rotating combs 33 a similar motion is imparted to the fibers until their ends are caught by the ends of the fibers already on the core when the fibers will be drawn through the comb and wrapped upon the core. After the fibers have been wrapped upon the core, the core is drawn downwardly by any suitable means (not shown) between the polisher blocks 34 which complete the wrapping of the ends of the fibers and give the covering a neat and finished appearance.

It will be understood that the invention herein described and illustrated is merely a useful and convenient form of the invention which is capable of many other modifications without departing from the spirit and scope of the invention.

What is claimed is:

1. In an apparatus for applying a fibrous covering to a core, means for feeding fibrous material to the apparatus at a predetermined rate, a wheel having a plurality of paddles and provided with pins on one of the paddles for separating the fibrous material into individual fibers, and means for applying the fibers to the core.

2. In an apparatus for applying a fibrous covering to a strand, means for conveying fibers to the strand, and a rotatable member

having a plurality of circular combs for applying the fibers to the strand.

3. In an apparatus for applying a fibrous covering to a strand, means for conveying the fibers to the strand, a rotatable member surrounding the strand, a circular comb mounted in the rotatable member, and second circular comb larger than the first mentioned comb and surrounding the latter, said combs cooperating with the rotatable member to apply the fibers.

4. In an apparatus for applying a fibrous covering to a strand, means for feeding a roving of fibrous material to the apparatus, a separating chamber, a paddle wheel in said chamber for separating the roving into individual fibers, a funnel-shaped outlet in the chamber, an applicator adapted to be supplied through the funnel-shaped outlet, and means for maintaining a current of air from the separating chamber into the applicator.

5. In an apparatus for applying a fibrous covering to a strand, means for conveying fibers to the strand, means for applying the fibers to the strand, a plurality of grooved blocks for polishing the fibers on the strand, and a pair of parallel hinges for each of said blocks to maintain them parallel with respect to each other.

6. In an apparatus for applying a fibrous covering to a strand, a stationary portion for supplying separated fibers, a rotatable portion having an aperture therein, and a removable section carrying the fiber applying mechanism adapted to be inserted in said aperture.

7. In an apparatus for applying a fibrous covering to a strand, means for supplying separated fibers, a rotatable portion for applying the fibers having an aperture therein, a removable section adapted to be inserted in said aperture, and means for retaining the removable section in position.

8. In an apparatus for applying a fibrous covering to a core, a chamber for receiving separated fibers, a rotatable housing connected therewith, a plurality of circular combs of different diameters mounted within the housing and rotatable therewith for combing the fibers, and suction means connected with the rotatable housing for causing a current of air to convey the fibers from the chamber through the plurality of combs and to apply the combed fibers to a core passing through the chamber, the combs and the housing.

9. In an apparatus for applying a fibrous covering to a core, an applicator unit, a rotatable supporting member having an aperture for receiving said applicator unit, and means for removably securing said applicator unit in the aperture in said rotatable supporting member.

10. In an apparatus for applying a fibrous covering to a core, an applicator unit, a ro-

tatable supporting member having an aperture for receiving said applicator unit, and spring means for removably securing said applicator unit in the aperture in said rotatable supporting member.

5 11. In an apparatus for applying a fibrous covering to a core, a polishing unit, a rotatable supporting member having an aperture for receiving said polishing unit, and spring means for removably securing said polishing unit in the aperture in said rotatable supporting member.

10 12. In an apparatus for applying a fibrous covering to a core, an applicator unit adapted to receive a core, polishing blocks disposed in said applicator unit adjacent the core, a rotatable supporting member having an aperture for receiving said applicator unit, and means for removably securing said applicator unit in the aperture in said rotatable supporting member.

15 In witness whereof I hereunto subscribe my name this 29th day of September, A. D. 1927.

20 P5 BRUNO MAX ALFRED TREBES.
